KITE

Raymond P. Holland, Jr., Kenmore, N. Y.

Application October 4, 1937, Serial No. 167,121

2 Claims. (Cl. 244—153)

While this invention has been developed in connection with the production of a kite, as that word is used in a somewhat restricted sense, as applicable to aerial structures which, either for purposes of recreation or for scientific purposes, are flown with an attached string or cord which leads to a fixed point or to the hands of an operator on the surface of the earth, it will be obvious as this description proceeds that the invention or some of the features of the invention are applicable also to free gliders which have no guiding string or even to self-propelled aeroplanes. The term "kite" is not to be taken in its usual restrictive sense, but in a broader sense which includes also gliders and aeroplanes. The general purpose of the invention is to produce a kite which will be more satisfactory in operation under varying conditions and requirements than has been produced hitherto. In accordance with the invention there is provided a preferably triangular member, with its sides converging toward the front which may be termed the body, lateral wings, preferably also triangular, which are hingedly connected to the body, are tilted with respect to the plane of the body, and are so connected, as by a strut, that as one wing tilts more or less from the plane of the body, the other wing will tilt correspondingly but in the opposite direction. To the underside of the body at its rearward and wider end are secured other members, preferably also triangular, which are united at their lower apices below the plane of the body, to form what may be called a keel. A bridle is connected at one end to the forward end of the body axis, where the leading edges of the wings meet, and at its other end to the apex or bottom of the keel. The leading string or cord is connected to the bridle at an intermediate point and leads thence to a fixed point or the hand of the operator at the surface of the ground or elsewhere.

The invention will be more fully explained hereinafter with reference to the accompanying drawings, in which is illustrated in a convenient and practical form a suitable embodiment of the invention.

In the drawings—

Figure 1 is a top plan view of the improved kite.

Figure 2 is a side view of the same.

Figures 3 and 4 are, respectively, a front end view and a rear end view of the same.

Figures 5, 6, 7 and 8 are views in outline, representing the positions and functioning of the wings under different conditions.

Figures 9-14 are detail views of various details of construction to be referred to.

The body *a* of the kite is a plane, preferably triangular, with its apex forward, formed of two rigid side members *a*¹, *a*², which converge forwardly and may be of wood or other suitable material, as are all of the frame members, and a member *a*³ at its rear or following end. The frame of this body has applied to it and secured in any suitable manner to form a plane, a sheet *a*⁴ of paper or other suitable fabric.

To each side frame member *a*¹, *a*² of the body *a*, at its forward or leading portion, one at each side, are hingedly connected, so that they may swing up or down with respect to the body, wings *b*, *b*¹⁵ preferably triangular, each of which may consist of frame members *b*¹, *b*², and in some cases a member *b*³, with a covering *b*⁴ of suitable material. The two wings *b*, *b*¹⁵, are tilted upward slightly with reference to the plane of the body *a* and are connected, the one to the other, by means such that as one wing is tilted upward with respect to the plane of the body *a* the other wing is tilted downward in corresponding degree. In Figures 1, 3, 4 and 5-8 such means is shown as a strut *c* which is pivotally connected at each end to the corresponding wing. In Figure 13 such means is shown as a strip *c*¹ of sheet metal, bent at the proper angle to conform to the dihedral angle of the wings and secured 30 to the frame members *b*¹ as by winding with tape *c*². To the underside of the body *a*, at its rear portion, are connected, hingedly or otherwise, one at each side, two keel members *d*, *d*³⁰, preferably triangular in shape, each being formed of frame members *d*¹, *d*² and *d*³ and a cover *d*⁴ of suitable material. The two keel members are brought together at their lower apices, as at *e*, materially below the plane of the body *a* and are secured together by any suitable means. 40 These members *d*, *d*³⁰, form a keel for the kite which is unchanged in position with respect to the body *a*, and at their apices provide for the attachment of the bridle *f* at a point which is materially below the plane of the body so that 45 there is afforded a leverage through which, by a pull on the flying string to one side or the other, when the kite is in flight, the body of the kite may be rocked in space to one side or the other.

A string or cord bridle *f* is connected at one end to the apices of the keel members, as at *e*¹, and at its other end is connected to the joint *g* where the forward inner apices of the wings *b*, *b*¹⁵, and the forward apex of the body *a* meet, and the 55

flying string h is connected to the bridle at a fixed point, as at i .

Referring now to the functioning of the wings in flying, as illustrated diagrammatically in Figures 5, 6, 7 and 8, it will be seen that when the pull of the flying string is directly downward, as represented in Figure 5, the two wings are symmetrically disposed with respect to the body; that when the flying string leads more and more to one side, as represented in Figures 6, 7 and 8, the body is rocked in space to one side or the other and the wings are tilted more and more with respect to the body of the kite, the wing opposite the direction in which the flying string leads being tilted more and more with respect to the body a toward a relatively horizontal position in which that wing has more uplift, while the other wing is tilted more and more in the opposite direction and has less uplift. The effect of such tilting of the wings under the influence of the pull of the flying string in maneuvering the kite will be readily apparent.

The formation of the several joints and connections may obviously be varied to suit convenience in construction and assemblage of the several main parts of the kite. Suitable details are shown in Figures 9-14.

The wings may be connected to the body of the kite, as at joint g , by rings or cords g^1 passed through transverse holes in the ends of the members, as shown in Figure 9. The attachment of the bridle f , as shown in Figure 9, is accomplished by a loop f^1 or cord around the joint. The pivotal connection of the strut c at each end to the corresponding wing may be accomplished by a cord passed through an eye in the corresponding end of the strut and lapped around the corresponding wing frame member b^1 . The joint at the outer ends of members b^1 and b^2 may be formed, as shown at b^5 in Figure 10, as by taping the members together, with the end of member b^2 placed above the end of member b^1 . The hinged joint at the rear of each wing b to the body member a^2 may be formed, as shown in Figure 11, by a ring or cord b^6 passed through a hole in the end of member b^2 and loosely around member a^2 . The connection of the keel member d^2 to member a^2 at this point may be effected by winding with soft wire, as shown in Figure 11.

Figure 12 shows the joint at e , where the keel members reach a common point, as formed by binding the members together by strips e^2 of gummed tape.

Figure 13 shows an alternative form of joint 5 at g . The ends of members a^1 , a^2 , b^1 , b^2 , are each wound with a short piece of soft wire, the free ends of which are twisted together. This creates a common point to which each of the four members is flexibly connected, the proper angle of tilt 10 of members b^1 to each other being assured by the bent metal strip c^1 , as above described.

In Figure 14 the wing member b^2 is shown as 15 flexibly connected directly to the main frame member a^2 by a soft wire a^4 , as in the construction shown in Figure 13, the keel member d^2 being connected to the frame member a^2 by tape, as at d^5 .

The rear end of the bridle may be looped, as at 20 e^1 in Figure 12, around the joint which connects the apices of the keel members d , and the connection of the forward end of the bridle to the joint at g may be effected by a loop, as described above and as shown in Figure 9. The flying string h may be secured to the bridle by a connector i , as shown in Figure 2.

It will be understood that various changes in 25 details of construction may be made to suit different conditions of use and that, except as pointed out in the accompanying claims the invention 30 is not restricted to the construction or any of the constructions hereinbefore described.

I claim as my invention:

1. In a kite, the combination of a body member, wings hingedly connected to the body member, means connected to the wings to maintain the wings in relatively tilted position, a keel extended downward from the body member, a bridle secured at one end to the forward end of the body member and at its other end to the bottom of the keel, and a flying string connected to the bridle. 40

2. In a kite, the combination of a body member, wings hingedly connected to the body member, and an angularly bent member having its parts secured respectively to the wings to maintain the wings in relatively tilted position. 45

RAYMOND P. HOLLAND, JR.
